W. H. WHEELER.

Wind-Mills.

No. 147,213.

Patented Feb. 3, 1874.

UNITED STATES PATENT OFFICE

WILLIAM H. WHEELER, OF BELOIT, WISCONSIN.

IMPROVEMENT IN WINDMILLS.

Specification forming part of Letters Patent No. 147,213, dated February 3, 1874; application filed April 1, 1873.

CASE A.

To all whom it may concern:

Be it known that I, WILLIAM H. WHEELER, of Beloit, in the county of Rock and State of Wisconsin, have invented a new and useful Improvement in Windmills; and I do hereby declare the following to be a full and exact description of the same, reference being had to the accompanying drawings forming part of this specification, in which—

Figure 1 is a perspective view of the apparatus on the upper part of the tower. Fig. 2 is a side elevation of the tower and part of the apparatus mounted on it. Fig. 3 is a sectional elevation of the upper part of the tower and the contained machinery. Fig. 4 is a plan view of the foot-plate in which the tubular axis of the vane is stepped. Fig. 5 is a detached elevation of the swiveled connection between the operating rope or chain and its extension. Fig. 6 is a transverse section of the box tower, and Fig. 7 is a plan view of the device for centering the wheel-support.

My invention relates to improvements in windmills, as hereinafter more fully set forth.

In the accompanying drawings, A is the plate or head, to one end of which the vane B is rigidly attached. This plate has projecting down from its under side a hollow axis, C, which passes through the cap of the tower C², and extends down within the tower to the rabbeted foot-plate C¹, in which said axis is stepped so as to revolve freely. D is the wind-wheel, of ordinary or suitable construction; D¹, its horizontal axis or shaft mounted upon a projection from the plate E, which plate is an eccentric continuation of the vertical axis of the wheel. The lower end E¹ of this vertical axis is hollow, and is stepped concentrically within a recess in the upper end of the axis C, so as to swing freely therein. The upper end E², also hollow, enters a sleeve, F¹, confined within a circular socket, F², formed upon an upward projection, F, of the plate A. The socket F² is held by the projecting arm F directly above the axis E¹, and by means of set-screws f the sleeve F¹ can be centered within the socket F²; I have, therefore, the means for keeping the vertical axis of the wheel in line with the vertical axis of the mill. As the

support of the wind-wheel is relieved from the weight of the vane by being pivoted upon the vane-support, the necessary changes in the position of the wheel in respect to the wind or vane are more easily and directly effected than if the vane were pivoted upon and obliged to move with the support of the wind-wheel. On the inner end of the shaft D¹ is a disk, D², having a wrist-pin connected by a pitman, i, with the actuating-rod G. This actuating-rod passes through the axis F², and also into the axis E¹ having an offset to clear the disk D².

As shown in Fig. 3, the lower end of the rod G forms a ring, G¹, embracing loosely a peripheral groove around the hollow head G² placed concentrically with the axes C E¹. The object of the swivel-joint between G and G² is to enable G to rotate with the wheel and vane, and G² to remain non-rotatory. From the lower end of G² two rods, G³, proceed downward at equal distances from the center of G² and on opposite sides thereof. These two rods pass through perforations x x, Fig. 4, in the foot-plate C¹, and by it are held from turning, but not from reciprocating up and down. At their lower ends these rods are fastened to the top of the pump-rod G⁴ at opposite sides, as shown in Fig. 1. The adjusting cord or chain g extends from a projection of the plate E horizontally to a sheave, k, mounted upon the top of an offset from one edge of the plate A, and thence to and over a sheave, l, mounted on A and projecting over the bores of the axes C E¹ far enough to drop the cord g into the exact center of said axes; therefore, said cord passes centrally through the head G² and centrally between the rods G³. At a point between the head G² and foot-plate C¹ the cord g terminates in an eye, m, on which is swiveled a head, n. (See Fig. 5.) From one side of the head n a rod, g', drops through the hole y, Fig. 4. This rod forms an extension of the cord g, and is the part laid hold of by the attendant on the ground. The rod g', it will be perceived, is not in the vertical center of the mill as the cord g is; but set off at one side thereof, in order to clear the rod G⁴. Nevertheless, when the rod g' is pulled, its force is passed to the cord g in the same man-

ner as though said rod were located centrally of the mill. As by offsetting the actuating-rod G the wrist upon the disk D² is brought directly over and in the same vertical line with the center of the head G² and pump-rod G⁴, the power of the wind-wheel is applied directly to the pump, thus avoiding loss of power and other inconveniences incident to side draft.

By the arrangement of the double connecting-rod G³ and head G² the cord or chain g may occupy the vertical center of the mill to the extent of the perpendicular range of said cord or chain, its lower end being swiveled, as shown, with an offset of the operating-rod g', for the purpose of allowing said cord or chain to revolve with the vertical axis C without twisting. It is plain, however, that if made strong enough one of the two offset connecting-rods G³ would answer the same purpose as two, both in respect to the line of draft from the wind-wheel to the pump-rod, and in allowing the cord or chain to occupy the vertical center of the mill, as above described. Therefore, I do not confine myself to the use of two offset-rods. Neither do I confine myself to any particular class of windmills in the use of the connecting and operating devices above described, as they are equally applicable to all mills which impart a reciprocating motion to a connecting-rod. In some instances a wire or rod may be substituted wholly or partly in the place of the cord or chain g.

Fig. 6 represents a section of the tower on which my windmill is mounted. It is in the form of a continuous box from top to bottom. I take ordinary fence-boards, H, of equal width, and placing four of these together in the manner shown in Fig. 6, form thus a section of my tower. One or more sets of iron

clamps, I, are fastened in the form of bands around the outside of the tower, and bolted together as shown in Fig. 6. By these bands the tower is very much strengthened. Eyes J are fastened into the bands, to which eyes the upper ends of wire stay-rods K are fastened. The lower ends of the stay-rods are attached to the heads of bolts L, which pass through plates M securely fastened to posts N, or pass through the posts themselves, set in the ground, one at each side of the tower, and at suitable distances therefrom. By a nut upon the outer end of the bolts L the slack of the stay-rods can always be taken up and the latter therefore kept always taut. The lower part of the tower may be secured by two parallel braces extending from foot of tower to two opposite posts, as shown, or in any other suitable manner.

What I claim as new is—

1. The combination of the plates A F, axes C E¹ E², sleeve F¹, socket F², and set-screws f, substantially as and for the purpose specified.
2. The combination of the actuating-rod G, wheel D, swiveled and hollow head G², double connecting-rod G³, plate C¹, and pump-rod G⁴, substantially as and for the purposes specified.
3. The adjusting-cord g, attached to the frame supporting the wind-wheel and passing through the central line of the axes C E¹, in combination with the swiveled extension-rod g', attached to the cord g at an offset, and the plate C¹, substantially as and for the purpose specified.

WILLIAM H. WHEELER.
